(57) **CLAIM**

The ornamental design for a panel for wireless backup camera as shown and described.

DESCRIPTION

FIG. 1 is a top, front and right side perspective view of a panel for a wireless backup camera showing my new design; FIG. 2 is a bottom, rear and left side perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is a top, front and right side perspective view thereof, shown with the camera of the panel for a wireless backup camera rotated in a first alternate position of use; and,

FIG. 10 is a top, front and right side perspective view thereof, shown with the camera of the panel for a wireless backup camera rotated in a second alternate position of use. The broken lines depict portions of the panel for a wireless backup camera that form no part of the claimed design.
